UNITED STATES PATENT OFFICE.

GEORGE HAZEL GUILD, OF CHICAGO, ILLINOIS, ASSIGNOR OF ONE-HALF TO OSCAR RATCLIFF, OF CHICAGO, ILLINOIS.

SMOKE AND SPARK DESTROYER.

1,016,491.

Specification of Letters Patent. Patented Feb. 6, 1912.

Application filed January 30, 1911. Serial No. 605,513.

To all whom it may concern:

Be it known that I, GEORGE H. GUILD, a citizen of the United States, and a resident of the city of Chicago, county of Cook, and 5 State of Illinois, have invented certain new and useful Improvements in Smoke and Spark Destroyers, of which the following is a specification.

My invention relates to improvements 10 in smoke and spark destroyers or preventers and more particularly to that class of preventers used in connection with locomotives, the object being to provide an improved smoke and spark preventing apparatus which shall be at all times under the control of the engineer or fireman in the locomotive cab.

A further object of my invention is to provide an apparatus as stated which shall 20 be simple of construction and efficient in operation.

Other objects will appear hereinafter.

With these objects in view my invention consists in the novel construction and arrangements of parts as will be hereinafter 25 described and claimed.

My invention will be best understood by reference to the accompanying drawings forming a part of this specification, and in 30 which—

Figure 1 is a side elevation of a locomotive provided with my improved smoke destroying apparatus, Fig. 2 is a transverse section of the locomotive stack showing a 35 portion of the smoke preventing apparatus, Fig. 3 is a vertical section taken on line $\alpha-\alpha$ of Fig. 2, and Fig. 4 is a vertical section taken on line $y-y$ of Fig. 2.

The preferred form of construction and 40 arrangement of my improved apparatus, as illustrated in the accompanying drawings, comprises a steam conveying pipe 1 which is arranged adjacent the exterior surface 2 of the locomotive boiler. The pipe 1 extends rearwardly to a portion 3 thereof which extends rearwardly through the shell 6 of the boiler to the locomotive cab 7 as clearly illustrated in Fig. 1. Connected 45 with the portion 3 of the pipe 1 is an upwardly extending pipe 8 which is connected to the steam space 9 of the boiler by means of a coupling 10 and control valve 11, the latter being situated within easy access of the locomotive men. The steam conveying 50 pipe 1 terminates at its forward end in a

vertically disposed pipe 12 which is connected by means of a coupling 12' to a vertically disposed pipe 13 arranged within the locomotive stack 14. The upper end of the pipe 13 terminates approximately in the middle of the stack 14 and is connected with a hollow steam receiving member 15 as clearly illustrated in Fig. 3. The member 15 is provided with curved ends 16 which conform to the interior surface of the stack 60 and are secured thereto by means of U-shaped clips 17 which embrace the ends 16 and are secured to the walls of the stack by means of rivets 18. Formed in the walls of the hollow member 15 is a series 65 of perforations 19 which are inclined so as to direct the steam which issues therefrom transversely of the stack 14 as indicated by arrows 20 in Fig. 2. The arrangement of the perforations 19 is such, that the sprays 70 of steam issuing therefrom will come in contact with practically all of the smoke and sparks which flow upwardly through the stack 14, thus tending to absorb the smoke and to cool the sparks below the 75 temperature of ignition.

In order to prevent overheating of the hollow member 15 caused by the hot smoke and sparks contacting therewith on the lower surface thereof, the same is substantially heart-shaped in cross section, as illustrated in Fig. 3, thus presenting a sharp or knife edge to the ascending smoke which is deflected. This conformation of the member 15 produces a minimum of resistance 80 to the upward flow of gases, and hence does not interfere with the draft of the locomotive.

It will be observed that since the portion 3 of the pipe 1 is protected by the boiler 85 shell 6 that steam flowing through said portion will not be condensed, consequently the full pressure of steam will be exerted in the steam sprays issuing from the perforations 19.

An apparatus of the construction set forth serves to effectually lessen the volume of smoke and sparks which issue from the locomotive stack, and, since the same is under the control of the locomotive engineer, is 105 a valuable accessory on a locomotive.

While I have illustrated and described the preferred construction for carrying my invention into effect, this is capable of variation and modification without departing 110

from the spirit of the invention. I, therefore, do not wish to be limited to the precise details of construction set forth, but desire to avail myself of such variations and 5 modifications as come within the scope of the appended claim.

Having described my invention what I claim as new and desire to secure by Letters Patent is:—

- 10 In an apparatus of the class described, the combination with a locomotive stack, of a hollow perforated member oblong in plan and adapted to spray steam, the ends of said member fitting said stack and the

sides thereof being heart-shaped in cross 15 section and transversing said stack, said ends being provided with perforations in their inner sides and said sides being provided with perforations in both sides; and clips securing the ends of said member to the 20 stack, substantially as described.

In testimony whereof I have signed my name to this specification in the presence of two subscribing witnesses.

GEORGE HAZEL GUILD.
